 a corporation of Kansas

Application April 23, 1948, Serial No. 22,843

4 Claims. (Cl. 230—114)

1

This invention relates to a blower structure. The structure is particularly useful as a blower for a warm-air furnace, but is applicable to a wide variety of uses.

Present day blowers, which are employed for warm-air furnaces, and other uses, are objectionable because of the noise developed in the operation of the blower, by reason of the amplitude and frequency of the compressible waves leaving the blower outlet. Further, such blowers are designed for use with conduits having a predetermined resistance. In actual operation, it is found that the resistance afforded by conduits often is considerably different than that for which the blower is designed and an unsatisfactory result obtains. Since the resistance in conduits varies with substantially every installation in a house or other building, there has been a long-felt need for some means for adjusting a direct drive blower to such varying resistance in the conduits, means being provided for an accurate adjustment from a position outside of the blower chamber.

An object of the present invention is to provide a blower structure which is effective for modifying the amplitude and frequency of compressible waves set up in the blower before leaving the blower outlet so as to greatly reduce the noise, while at the same time providing a highly efficient blower. A further object is to provide a blower structure equipped with means operable from without the blower chamber for easily and accurately adjusting the output of the blower against the resistance encountered in a particular conduit installation. A still further object is to provide means for accurately dividing the output of the blower so as to recycle a portion of the output when the pipe resistance is less than that for which the blower is designed. Yet another object is to provide a blower structure equipped with means for dampening vibrations and for sealing the casing about the operating parts to obtain a high efficiency, while producing less noise and while providing a calibrated arrangement for accurately adjusting the output of the blower against the pipe resistance encountered. Other specific objects and advantages will appear as the specification proceeds.

The invention is illustrated, in a single embodiment, by the accompanying drawings, in which—

Figure 1 is a top plan view of apparatus embodying my invention; Fig. 2, a side view in elevation and providing a vertical sectional view of the blower structure, the section being taken as

2

indicated at line 2—2 of Fig. 1; Fig. 3, a broken end view in elevation; and Fig. 4, a perspective view of the cut-off block or roll with the supporting means therefor.

5 In the illustration given, A designates a motor and B a blower structure.

The motor A is of well-known construction and need not be described in detail. It is supported upon a frame 10, provided with rubber supporting blocks 11 which dampen the vibrations of the motor A. The motor A drives a shaft 12.

10 The blower structure B may be of any suitable construction. In the illustration given, there is secured upon the motor shaft 12 an impeller arm 13 fixed to a central frame member 14, to which are secured curved vanes 15. The impeller or blower is also provided with end plates 16 to which the vanes 15 are secured at 15 their ends.

15 About the impeller or blower, there is provided a casing 17, which forms an annular chamber 18 of relatively small cross-section at the top of the blower but enlarging toward the outlet pipe 19, as shown in Fig. 3. Sealing strips 21 are secured to the casing members 17 and extend inwardly to form curved inlet openings 22 leading into the interior of the blower. Inlets are thus provided from both sides of the structure.

20 The casing 17, as shown more clearly in Fig. 2, is stepped inwardly at 23, and then extends outwardly, terminating in an outwardly-turned flange 24. A metal sheet 25 is welded to the flanges 24 to close the casing.

25 Secured upon the stepped portions 23 of the casing is a sheet 26 of metal or other suitable material, providing a chamber between it and the sheet 25. The sheet 26 is preferably provided with perforations 27, and the chamber between the sheets 25 and 26 is preferably filled with fibrous material, as, for example, fiber glass 28. Each end of the chamber housing the fiber glass 28 may be closed by a metal plate or cap 29, as shown more clearly in Fig. 3.

30 In order to adjust the volume of the air or other fluid leaving the blower outlet or mouth, I provide a cut-off block or roll 30. The roll 30 is secured to the arcuate arms 31 by means of the screws 32. Each of the arms 31 is provided with a series of locking slots or notches 33 on the underside thereof. A cross-strip 34 is secured to the outer ends of the arms 31 to provide a handle 35 therefor. The casing 17, at the top of the blower

structure, is provided with spaced guides 35 having slots 36 receiving and guiding the screwheads 32. A baffle 37 may be provided between the flange extensions 35 to partially seal off the return passage to the blower chamber.

Secured to the casing 17 is an adjustable latch 39, equipped with an elongated slot 40 through which extends a screw 41. Upon loosening the screw 41, the tooth 42 of latch plate 39 may be withdrawn to permit shifting of the arcuate arms 31 forwardly or rearwardly to bring the roll 30 to a desired position, and then the latch plate 39 may be moved into engagement with the aligned notch 33 and secured therein by rotating the screw 41 into locking position.

The frame 10, which supports the motor, is preferably extended to provide a base also for the blower B, as shown more clearly in Fig. 1, and resilient sleeves 43 are preferably employed, as illustrated more clearly in Fig. 1, for providing a resilient support for the blower casing 17. It will be understood that the supporting structure may be varied widely to meet different requirements for the apparatus.

Operation

In the operation of the structure, the motor drives the impeller or blower through the impeller arm 13. Air is drawn inwardly from the sides of the structure and into the impeller, and is delivered into the annular chamber of the blower. The perforated sheet or lining 26 tends to diffuse or split up the compressible waves, and the fibrous material 28 slows down or modifies the amplitude and energy of the compressible waves leaving the blower outlet. As a result, I find that the noise of the blower is greatly reduced, while at the same time the desired volume of air is delivered with high efficiency.

If the resistance of the conduits with which the blower is connected, is less than that for which the output of the blower was designed, the block or roll 30 may be advanced from its position shown in Fig. 3 to a position extending farther into the outlet of the chamber 18. Such movement decreases the ability of the blower to compress the air and adjust the output of the blower to the resistance encountered. The air tends to cling to the outer periphery of the impeller or wheel and the cut-off block apparently serves as a stripper for stripping off the clinging air. When the cut-off block is moved rotationally around the rotor or impeller and away from the narrowest point between the rotor and the casing or scroll, it is less effective in stripping off the stream of air and more of the air clings to the wheel. Such air may be returned through the return portion of the annular chamber. Whatever be the explanation, the movement of the cut-off block is found to give an accurate adjustment of the blower to the resistance in the conduits, and such adjustment is effected easily and accurately by moving the handle structure supported outside of the blower. Movement of the handle, which effects a corresponding movement of the block within the blower, provides ready and easy means for giving the exact balance needed between the blower and the pipe resistance encountered.

To adjust the roll or block 30, the screw 41 is loosened, and the handle 34 outside of the casing is advanced to project the arcuate arms 31 and the roll 30 farther into the mouth of the chamber. Ordinarily, such resistance will be known by the

length and size of the conduits and such resistance, upon reference to a chart, will enable the operator to adjust the roll accurately to the desired point to meet such resistance. The various notches 33 may be provided with scale numerals to aid in such ready adjustment to meet the precalculated resistance afforded by the conduit. The latch plate 39 will then be moved to bring the tooth 42 thereof into the appropriate notch, and the screw 41 will be rotated to secure the plate in the selected position. If at any later time the length and size of the conduits should be changed, a ready readjustment of the divider or cut-off block may be made.

The cut-off block may be of any desired shape or construction. I prefer to employ a roll or a block having curved surfaces to facilitate the flow of the divided air streams.

While, in the foregoing specification, I have set forth a specific structure in great detail for the purpose of illustrating one embodiment of the invention, it will be understood that such details of structure may be modified widely by those skilled in the art without departing from the spirit of my invention.

I claim:

1. In a blower structure, a vane-equipped impeller mounted for rotation, a generally cylindrical casing providing an annular chamber about said impeller enlarging toward an outlet with which it is provided and having also an inlet leading into the interior of the impeller, an arcuate track extending into said chamber adjacent the outlet, arcuate arms supported by said track, a cut-off block carried by said arms, and means associated with said arms and extending out of said casing chamber for moving said arms transversely of said chamber, said arcuate arms being provided with a portion equipped with notches and an adjustable latch for engaging said notches.

2. In a blower structure, a vane-equipped impeller mounted for rotation, a casing providing an annular chamber about said impeller, the chamber enlarging toward an outlet with which it is provided and having also an inlet communicating with the interior of said impeller, a cut-off block within the outlet portion of said chamber, and arcuate members guided upon said casing and supporting said block within said chamber and for movement transversely of said chamber, one of said arcuate members being provided with notches and a scale aligned with said notches and said casing being provided with an adjustable latch for engagement with said notches.

3. In a blower structure, a vane-equipped impeller mounted for rotation, a generally cylindrical casing providing an annular chamber about said impeller enlarging toward an outlet with which it is provided and having also an inlet leading into the interior of the impeller, said casing providing a return passage from said outlet to said chamber, and a cut-off block arranged axially of the impeller and being substantially coextensive in length therewith and adjacent its periphery, said cut-off block being mounted adjacent the outlet passage at said return passage and entirely within the outlet for movement in an arcuate path substantially concentric with the impeller axis bodily outwardly into said chamber outlet for dividing the output of said impeller so that a portion of the output is returned through said return passage to said chamber, said cut-off block having a relatively small

transverse length as compared with the transverse length of said outlet so that the area of said outlet in communication with said impeller remains substantially constant irrespective of the position of the cut-off block.

4. In a blower structure, a vane-equipped impeller mounted for rotation, a casing providing an annular chamber about said impeller, the chamber enlarging toward an outlet with which it is provided and having also an inlet leading into the interior of the impeller, said chamber having a return passage from the outlet thereof to the narrow portion of the chamber, and a cut-off block arranged axially of the impeller and being coextensive in length therewith and adjacent its periphery, said cut-off block being mounted adjacent the wall of said outlet at said return passage and entirely within the outlet for movement in an arcuate path concentric with the impeller axis bodily outwardly into said chamber outlet for dividing the output of said

impeller so that a portion is returned through said return passage to said chamber, said cut-off block having a relatively small transverse length as compared with the transverse length of said outlet so that the area of said outlet in communication with the impeller remains substantially constant irrespective of the position of the cut-off block.
